UNITED STATES PATENT OFFICE.

SAMUEL S. CAMPBELL AND JOSEPH H. EASTMAN, OF BOSTON, MASS.

SHIP'S SIGNAL.

SPECIFICATION forming part of Letters Patent No. 240,504, dated April 26, 1881.

Application filed July 19, 1880. (No model.)

To all whom it may concern:

Be it known that we, SAMUEL S. CAMPBELL and JOSEPH H. EASTMAN, of Boston, in the county of Suffolk and State of Massachusetts, have invented a new and useful Improvement 5 in Ship-Signals, of which the following is a specification.

Our invention relates to certain improvements in signaling apparatus for vessels used 10 for indicating the course of a vessel by means of a sounding-instrument, or by flashes of light during a fog or at night. The system employed by us is similar to that described in Patent No. 220,231, granted to J. W. Fowle, 15 the several points of compass being indicated by sounds repeated at certain intervals, according to an established system to be understood and adopted on all sea-going vessels—a single tone, repeated at constant regular intervals, 20 to indicate that the course of the vessel-signaling was due north; one note, a pause, and two notes would indicate a northeast direction; one note, a pause, and three notes would indicate north, northeast, and so on through the 25 several points of compass.

Our invention consists in an improved construction of the toothed cylinder and the operative mechanism whereby the space occupied by the apparatus is very much reduced, 30 and the instrument rendered more certain in action and less liable to get out of order than the apparatus described in the above-named patent.

Referring to the drawings, Figure 1 represents a side elevation of an apparatus embodying our improvements. Fig. 2 is a partial sectional view, enlarged, of Fig. 1 on the line *xx*. Fig. 3 is a view of the bell hammer and arm, shown enlarged. Fig. 4 shows a lantern for 40 signaling by a flash light.

A represents the cylinder, which is composed of a series of annular sections, *a*, between each one of which is a disk or flange, *b*, of larger diameter than the sections *a*, so as to extend 45 beyond the same and form a series of grooves or channels around the several sections of the cylinder *A*. The several sections *a* of the cylinder *A* are cast with the cam-shaped teeth or projections *c*, as shown in Fig. 2, the number 50 of teeth on each section corresponding to the number indicating the point of compass to be

signaled. This form of tooth enables it to act readily and easily upon the arm that actuates the signaling apparatus. By making the cylinder in sections and casting them with the teeth, instead of a solid cylinder with teeth inserted in the same, we gain greater strength, and in case any of the teeth become broken or injured, so as to be unfit for use, a new duplicate section can be readily substituted. A portion of each flange *b* is cut away, as shown at *b'*, Fig. 2, in order to allow the arm *L*, herein-after described, to be moved along the cylinder, so as to be adjusted to any desired section or set of teeth. The cylinder *A* is mounted on a 65 shaft, *C*, which is rotated by means of a system of clock-work, or by any power applied thereto.

B represents an index-plate, arranged in front of the cylinder *A*, as shown, and is secured to the frame *F*. On the upper side of the index-plate *B* are marked the several compass-points, below each of which are the figures denoting the number of strokes to be struck, and corresponding with the number of teeth on the section of the cylinder to which they are opposite. On the under side of the upper portion of the index-plate *B* is a series of notches, each notch corresponding with a section of cylinder *A*.

I is a rock-shaft, made square in section, and is supported in hangers or brackets *K K*, so as to admit of its being rotated or turned in its bearings.

G G' represent a pointer or indicator, arranged to slide laterally on the lower bar, *B'*, of the index-plate *B*, upon which it is supported, as shown in Fig. 2. At the rear of the upper end of the pointer *G* is a pin, *e*, which fits in the notches on the under side of the upper portion of the index-plate *B*, and serves to lock the index or pointer in place. The indicator or pointer *G* is held up by means of a spring, *M*, attached to lever *L*, and is drawn down by pressing upon the thumb-piece *H* to 90 unlock the pin *e* from the notches in index-plate *B*, a slot, *f*, in the part *G'* of the pointer, allowing of the free movement of said spring *M*.

Upon the rock-shaft *I* is fitted an arm or lever, *L*, so as to admit of its being easily moved laterally on said rock-shaft. The lever *L* extends toward the cylinder *A*, its free end be-

ing nearly in contact with said cylinder and between the flanges or extensions of disks *b*, so as to be operated by the teeth on the cylinder as it rotates. It will be seen that as the 5 lever *L* is actuated by the teeth on the cylinder *A* it will impart to the rock-shaft *I* a partial rotation by the impact of each tooth on said cylinder. A pin, *h*, on the front end of lever *L* plays in a slot, *g*, in the pointer-frame *G'*.

10 *O* represents a bell or gong, arranged at the rear of the end of the cylinder *A*.

Upon the rock-shaft *I*, near its end, by the bell *O*, is fixed an arm, *N*, (shown enlarged in Fig. 3,) carrying the hammer *N'*. *P* is a 15 spring for holding the hammer-arm in place.

It will be seen that as the hammer-arm *N* is made fast to the rock-shaft *I* every partial rotation of the latter will move the arm *N* and cause the hammer *N'* to strike the bell 20 *O*, and as the rock-shaft *I* is partially rotated at each impact of the lever *L* with the teeth *c* on the rotating shaft *A*, it follows that at every passage of the lever *L* over the teeth *c* a blow will be struck on the bell or gong, thus 25 indicating, by the number of strokes, the course the vessel is sailing.

In order to provide more effectually for indicating the course of a vessel at night, we connect the signaling apparatus with a flash 30 light, so arranged that the several numbers indicating any particular course will be represented by a corresponding number of flashes of light, which is effected as follows:

Q represents a lantern, and is provided with 35 a frame or casing, *T*, which is arranged to slide over the lantern and expose or conceal the light at will, the spring *U* serving to retract the lantern within the casing *T* after exposure. Any of the ordinary methods of producing a 40 flash light may be employed. This lantern may be placed at the bow of a vessel, or in any other suitable part of the same, as required.

To the lower end of the casing *T* is attached a cord or rope, *L*, which is connected to the 45 hammer-arm *N*, as shown in Fig. 3, so that every time the said arm is moved by the partial rotation of the rock-shaft *I* to sound the bell the cord *R* will draw the casing *T* down and expose the light, the said casing returning to conceal the light as the arm *N* resumes its normal position.

Instead of being attached to the hammer-arm *N*, a separate arm or lever may be secured

to the rock-shaft *I*, for operating the cord *R* and casing *T*, if desired.

55 In the drawings, Fig. 1, the pointer is set upon the index-plate to designate the course of the vessel as S. E., with the figures 3 1, indicating three blows on the bell, or three flashes of light, a pause, and one blow or flash. When 60 the course of the vessel is to be changed the pin *e* is drawn down out of its notch by operating the thumb-piece *H*. The pointer is then slid along on the lower bar, *B'*, of the index-plate to such position as required, and the 65 pin *e* enters the corresponding notch and locks the pointer.

The flanges *b* serve as guides to the lever *L*, to prevent any lateral movement of the same, as without such provision the signals would 70 be liable to become changed, on account of the motion of the vessel or by accident in adjusting the signals.

When the apparatus is used on a steamer a connection may be made with a steam-whistle, 75 so as to signal by sounds from the whistle, in the place of, or in addition to, the striking of a bell or the flashes of light.

What we claim as our invention, and desire to secure by Letters Patent, is—

80 1. In a signaling apparatus for vessels, the combination, with the sectional cylinder *A*, provided with the teeth *c*, of a stationary index-plate, *B*, extending the whole length of cylinder *A*, the laterally-adjustable pointer *G* 85 *G'*, the rock-shaft *I*, adjustable lever *L*, and the bell-striking device, substantially as and for the purpose set forth.

2. The laterally-adjustable lever *L*, in combination with the rock-shaft *I*, the hammer-arm *N*, and the sectional toothed cylinder *A*, as and for the purpose specified.

90 3. In a signaling apparatus for vessels, the toothed cylinder *A*, made in sections separated from each other by flanges *b*, extending above 95 the surface of the cylinder, so as to form guides for the lever actuated by the teeth on the cylinder, substantially as set forth.

In testimony whereof we have signed our names to this specification in the presence of 100 two subscribing witnesses.
